UNITED STATES PATENT OFFICE.

JOSEPH A. O'LAUGHLIN, OF HUTCHINSON, KANSAS.

SINK TRAP AND LIFT.

Application filed April 9, 1924. Serial No. 705,328.

To all whom it may concern:

Be it known that I, JOSEPH A. O'LAUGHLIN, a citizen of the United States, residing at Hutchinson, in the county of Reno and State of Kansas, have invented certain new and useful Improvements in a Sink Trap and Lift, of which the following is a specification.

This invention appertains to novel improvements in combination water traps and lifts and the primary object of the present invention is to provide novel means for lifting water from waste traps in basements and the like to the sewer pipe, said means including a novel device for automatically preventing the backing up of the water in the trap and the consequent flooding of the basement should the sewer become stopped up or in any other way rendered unfit to carry away the sewage.

Another prime object of the invention is the provision of an automatic lift for water traps including a novel valve arrangement so constructed as to permit the flowing of the water up past the same to the sewer pipe but prevent the downward flow of water past the same into the trap.

A further prime object of the invention is the provision of a drain of a non-automatic or of an automatic construction within an airtight casing connected to a laundry drain or cesspool for facilitating the lifting of the water for a considerable distance above the laundry drain or cesspool.

A further prime object of the invention is the provision of novel means for changing the drain either into an automatic device or into a non-automatic device, the drain when constructed to work automatically embodying a valve controlled float, which is arranged to operate to shut off the connection between the drain and the trap when the water in the trap falls below a predetermined level.

A still further object of the invention is to provide an improved device of the above character, which will be durable and efficient in use, one that will be simple and easy to manufacture, and one which can be incorporated in a plumbing system at a small cost.

With these and other objects in view, the invention consists in the novel construction,

arrangement and formation of parts, as will be hereinafter more specifically described, 55 claimed and illustrated in the accompanying drawings, in which drawings:

Figure 1 is a fragmentary side elevation of my improved drain and trap connected with a plumbing system, the drain being 60 shown of a non-automatic construction, the trap being shown in cross section.

Figure 2 is an enlarged vertical section through the improved drain portion of the invention, the drain being of a non-automatic 65 character.

Figure 3 is a detail horizontal section through the drain taken on the line 3—3 of Figure 2, and

Figure 4 is an enlarged vertical central 70 longitudinal section through the improved drain constructed to operate automatically.

Referring to the drawings in detail, wherein similar reference characters designate corresponding parts throughout the 75 several views, the letter A generally indicates the improved trap and drain and B a plumbing system with which it is incorporated.

As clearly shown in Figure 1 of the drawings, the plumbing system B includes a laundry drain or sink 5 located in a basement or the like below the main sewer pipe 6. As shown, water is supplied to the laundry tub or sink 5 by means of supply pipes 85 7 one of which, preferably the cold water pipe has connected thereto a branch pipe 8 which leads to a part of the improved drain and trap A, as will be hereinafter more fully described. The outlet of the 90 laundry tray or sink 5 is connected to the trap and drain A by means of a pipe 9 which will be also hereinafter more fully described.

The improved trap and drain A shown 95 in Figures 1 to 3 of the drawings is of the non-automatic nature and consequently a hand operated globe valve or the like 10 can be incorporated in the length of the pipe 8 for controlling the flow of water there- 100 through to the drain.

The drain and trap A comprises an outer casing 11 which can be of the airtight nature and to which has connected at the lower end thereof the drain pipe 9 from 105 the sink or laundry tray 5.

Disposed axially within the airtight casing 11 is the drain portion 12 per se of my invention. This drain portion 12 embodies a tubular outer shell 13 to which is threaded-
5 ly or otherwise connected an outlet cap 14 at its upper end. This outlet cap 14 in turn supports an inner tubular sleeve 15 which comprises the portion through which the water or other sewage is adapted to flow.
10 The upper end of the sleeve 15 has connected thereto the outlet sewer pipe 16 which extends to the main sewer pipe 6. It is to be understood at this point that my invention is particularly adapted for use in
15 basements, cellars and the like where the main sewer pipe is located above a cesspool, laundry tub or the like so as to insure the effective carrying off of the water from the basement to the main sewer and thus prevent
20 the flooding of the basement.

Arranged within the sleeve 15 at a point intermediate its ends I provide a valve seat 17 having an axial way 18 therethrough. A ball valve 19 is adapted to normally fit upon
25 the seat 17 and the provision of this seat and valve forms one of the most important features of my invention. The lower end of the tubular pipe or housing 13 is closed by a removable cap 20, when the device is of a
30 non-automatic nature as shown in Figures 1 to 3 inclusive. The lower end of the sleeve 15 can have connected therewith in any preferred way a nozzle 21 which is arranged below the valve seat 17. A plurality of
35 ports 22 are formed in the tubular pipe or housing 13 and communicate with the inner sleeve 15 below the valve seat 17. These ports permit the flow of the sewage from the casing 11 into the inner sleeve 15.
40 The water branch feed pipe 8 is connected with the cap 14 and the upper end of the tubular pipe or housing 13 as is clearly shown in Figure 2 of the drawings.

In operation of the improved drain and trap, when it is desired to carry the water off from the casing 11, which has collected therein from the sink tub or the like 5, the valve 10 is open which permits the flow of water between the tubular pipe or housing
45 13 to the inner sleeve 15. This water will flow down to the lower end of the drain and then up through the nozzle 21 through the sleeve 15, up the pipe 16 and into the sewerage 6. This flow of water will unseat the valve 19 and cause a suction in the ports 22 which will suck in the water from the casing 11 and thus effectively raise the same to the main sewerage pipe 6. If for any reason the sewerage pipe 6 is prevented from carrying off the water and other sewage and if the water and sewage from the main pipe 6 starts to back up in the drain, the valve 19 will be forced on its seat 17 which will effectively prevent the collecting of the sewage
55 60 65 into the casing 11 from the main sewerage

pipe 6. This will, of course prevent the flooding of the basement or cellar and thus effectively obviate this trouble.

While I have shown the improved trap and drain connected with a laundry tub or sink 5, it is to be understood that the same can be connected with a cesspool and in fact the casing 11 can form the cesspool by simply sinking the same level with the floor of the cellar or basement and provide recesses in the upper wall of the casing.

In Figure 4 of the drawings I have shown the automatic arrangement for the drain and this drain is constructed identically with the drain shown in Figures 1 to 3 inclusive with the exception that the lower cap 20 is removed to the automatic device incorporated with the tubular housing 13 in lieu of said cap.

As shown the automatic drain comprises an outer tubular housing 25 to which is connected at its outer end a cap 26 for supporting the inner sleeve 27 which leads to the sewerage pipe 6. The cap 26 also receives the branch water pipe 8 as in the drain previously described. At a point above its lower end, the sleeve 27 is provided with a valve seat 28 on which is adapted to seat the ball valve 29. The extreme lower end of the sleeve 27 is provided with a combined nozzle and valve seat 30 on which is adapted to fit the sliding valve head 31, which is connected to an operating plunger 32. The plunger 32 is slidably mounted in a suitable packing gland 33 carried by the cap 34 which is threaded with the lower end of the tubular housing 28. Suitable ports 35 are provided for permitting the flow of the sewage from the casing 11 into the sleeve 27 between the valve seats 28 and 30. As shown these ports 35 include short lengths of tubes which extend through the tubular housing 25 and the sleeve 27.

A float 36 of annular construction is slidably mounted on the tubular housing 25 and is adapted to be raised and lowered by the water in the casing 11. The lower end of the float 36 has rigidly connected thereto at diametrically opposite points depending arms 37 which are in turn connected by a pin and slot connection 38 with levers 39 which are pivoted as at 40 to depending supporting brackets 41 carried by the cap 34. The inner ends of the levers 39 are pivotally connected as at 42 to the plunger 32 of the valve head 31.

Now it is obvious that when the casing 11 becomes filled with water that the float 36 will be raised which will move the valve body 31 below and off of the seat 30 which will permit the flow of the water from the branch pipe 8 to enter into the sleeve 27 and force the valve 29 from its seat, which will suck the water from the casing 11 and as soon as the water or other sewage in the

casing 11 falls below a predetermined level, the float 36 will fall and thus seat the valve body 31 and prevent the water flowing further through the valve seat 30 into the sleeve 5 27.

From the foregoing description, it can be seen that I have provided an exceptionally simple and durable means for insuring the effective lifting of water from traps and 10 the like to overhead sewerage pipes which will effectively prevent the backing up of the water into the trap from the sewerage pipes should the same become clogged up through any cause.

Changes in details may be made without departing from the spirit or the scope of 15 this invention.

What I claim as new is:

1. In a combined trap and water drain 20 for plumbing systems, a casing having an inlet therein for receiving sewage, an axially disposed tubular housing extending into the casing, an axially disposed sleeve arranged within the housing and extending 25 exteriorly thereof for connection with the sewer pipe, a water supply pipe communicating with the upper end of the housing and arranged for permitting the flow of water around the lower end of the sleeve 30 and up into the sleeve, and inlet ports communicating with the sleeve for permitting the sucking of water into the sleeve from the casing.

2. In a trap and water drain for plumbing 35 systems, a casing, a tubular housing extending axially within the casing, a cap closing the upper end of the housing, a sleeve disposed axially within the housing and carried by the cap and extending exteriorly 40 thereof for connection with the sewer pipe, a cap for the lower end of the housing disposed below said sleeve, ports formed in the sleeve and housing for permitting the flow of water from the casing into the sleeve, a

feed water pipe communicating with the 45 upper end of the housing for permitting the flow of water between the housing and sleeve and up through the sleeve for creating a suction in said ports, a valve seat disposed within the sleeve above said ports, and a 50 valve arranged to normally rest upon said seat.

3. In a trap and drain for plumbing systems, an axially disposed tubular housing arranged to fit within the trap, a spaced tubular sleeve fitted within the housing, a cap carried by the upper end of the housing for supporting the sleeve, a sleeve extending exteriorly of the cap for connection with the sewer pipe, a cap carried by the lower end of 60 the housing arranged below the lower end of the sleeve, and valve seat arranged within the sleeve above the lower end thereof, a valve arranged to normally fit upon said seat, and lower valve seat connected to the 65 lower end of the sleeve, waste water inlet ports extending through the housing and communicating with the interior of the sleeve for permitting the flow of water into the sleeve from the trap with which the 70 housing is associated, a float slidably mounted upon the housing adapted to be raised and lowered by water in the trap with which the housing is associated, a sliding valve for fitting upon the lower valve seat, means 75 operatively connecting the sliding sleeve with the float, and a feed water pipe connected with the upper end of the housing, the sliding valve adapted to control the flow of the feed water through the lower valve 80 seat.

In testimony whereof I affix my signature in presence of two witnesses.

JOSEPH A. O'LAUGHLIN.
